HEAT EXCHANGER OR SIMILAR ARTICLE

Horace C. McSwain, 703 Westwood,
Richardson, Tex. 75080

Filed July 25, 1969, Ser. No. 18,410

Term of patent 14 years

Int. Cl. D23—03

U.S. Cl. D23—127

FIG. 1

FIG. 2

FIG. 3

FIG. 4

FIG. 1 is a perspective view of a heat exchanger or similar article showing my new design;

FIG. 2 is a perspective view of the opposite face thereof;

FIG. 3 is a plan view of the face shown in FIG. 1; and FIG. 4 is a plan view of the face shown in FIG. 2.

I claim:

The ornamental design for heat exchanger or similar article, substantially as shown and described.
